UNITED STATES PATENT OFFICE.

JACOB A. THOMAS, OF READING, PENNSYLVANIA.

DESIGN FOR A BEARING-SCREW FOR SHADE-ROLLERS.

SPECIFICATION forming part of Design No. 28,802, dated June 7, 1898.

Application filed April 29, 1898. Serial No. 679,248. Term of patent 7 years.

To all whom it may concern:

Be it known that I, JACOB A. THOMAS, a citizen of the United States, residing at Reading, in the county of Berks and State of Pennsylvania, have invented and produced a new and original Design for a Bearing-Screw for Shade-Rollers; and I do hereby declare the following to be a full, clear, and exact description of the same, reference being had to the accompanying drawing, forming a part thereof.

In the accompanying drawing the figure is a perspective view of a bearing-screw for shade-rollers embodying my design.

The leading feature of my design consists of a cylindrical body portion or shank provided with a screw-threaded end, the other end of the shank being turned downwardly, then outwardly and upwardly, and then inwardly to form an open head or loop.

A in the drawing represents a cylindrical

body portion or shank formed with a sharpened screw-threaded end a , the upper end of the shank being turned downwardly, as at a' , and then outwardly, as at a^2 , and then upwardly, as at a^3 , and then inwardly, as at a^4 , to form an open loop, with an entrance-passage a^5 between the portion a^4 and the shank A.

Having now described my invention, what I claim as new, and desire to secure by Letters Patent, is—

The design for a bearing-screw for shade-rollers, substantially as herein shown and described.

In testimony whereof I hereunto affix my signature in presence of two witnesses.

JACOB A. THOMAS.
